Int. Cl. D30—01

U.S. Cl. D30—37

FIG. 1

FIG. 3

FIG. 1 is a side elevation of a protective garment for dogs, showing my new design, the view illustrating how the garment is worn by a dog, the dog being shown in dash lines;

FIG. 2 is a plan view of the garment, opened up; and FIG. 3 is an end view thereof.

FIGS. 1 and 2 are lined for the iridescent color, here red.

I claim:

The ornamental design for a protective garment for dogs, substantially as shown and described.
